Fig. 3.

Fig. 4.

FIGURE 1 is a front elevational view of a portable liquid storage tank showing my new design;

FIGURE 2 is a top plan view thereof;

FIGURE 3 is an elevational view taken from the right side thereof;

FIGURE 4 is a bottom plan view thereof, the hose being broken away for convenience of illustration;

FIGURE 5 is a front elevational view of a modified form of the portable liquid storage tank shown in FIGURE 1, the top right corner being broken away for convenience of illustration;

FIGURE 6 is a top plan view of FIGURE 5;

FIGURE 7 is a bottom plan view of FIGURE 5;

FIGURE 8 is an elevational view taken from the right side of FIGURE 5, the hose being broken away for convenience of illustration; and

FIGURE 9 is an elevational view taken from the left side of FIGURE 5.

The undisclosed rear of the portable liquid storage tank is substantially concave and unornamented, as indicated by FIGURES 3, 8 and 9.

I claim:

The ornamental design for a portable liquid storage tank, substantially as shown and described.
